H. E. SMITH,
RAILWAY MAIL DELIVERY,
APPLICATION FILED JULY 28, 1919.

1,353,284.

Patented Sept. 21, 1920.

UNITED STATES PATENT OFFICE.

HERBERT E. SMITH, OF SPOKANE, WASHINGTON, ASSIGNOR TO SPOKANE MAIL EQUIPMENT COMPANY, OF SPOKANE, WASHINGTON.

RAILWAY MAIL-DELIVERY.

1,353,284.

Specification of Letters Patent. Patented Sept. 21, 1920.

Application filed July 28, 1919. Serial No. 313,936.

To all whom it may concern:

Be it known that I, HERBERT E. SMITH, a citizen of the United States, residing at Spokane, in the county of Spokane and State of Washington, have invented certain new and useful Improvements in Railway Mail-Delivery, of which the following is a specification.

My present invention relates to improvements in railway mail delivery and especially to that part of the equipment carried by the railway car for delivery of the mail pouch to coöperating mechanism located at the railway station, and the device of the present invention is especially adapted for use in connection with the device forming the subject matter of another invention and contemporary application for patent. While the present device is especially adapted for use as described, yet it is capable of effective operation and manipulation in the delivery of mail pouches in connection with other acceptable railway mail devices now in use.

The present invention involves the utilization of a simple construction and structure whereby the shock of impact, received as the mail is exchanged, is absorbed as the oscillatable or rotatable delivery device swings, by a pair of springs, and the pouch supporting arms are also provided with release devices providing novel combinations and arrangements of parts as will be herein-after explained.

In the accompanying drawings one complete example of the physical embodiment of the invention is illustrated, the delivery device being depicted as attached at one end of a railway car especially adapted for one track travel, the device being located at the front and left side of the car so that the impact of receiving a pouch will swing the crane or delivery arms around to the doorway. A spring is provided to hold the crane or delivery device in projected position, and an operating lever is utilized to pull the crane in, when not under impact, all as will be more particularly specified and claimed.

Figure 1 is a view in elevation showing the rotatable delivery device swung in to position for access from the doorway of the car.

Fig. 2 is a view taken transversely of the car showing the open doorway, the delivery

device in position of Fig. 1, and showing also the lever for pulling and the mechanism for holding the delivery device in position at the doorway.

Fig. 3 is a top plan view of the device in projected position ready to exchange mail pouches.

Fig. 4 is a detail view of one of the pouch retaining and releasing devices on the delivery arms.

The rotatable delivery device as carried by the car C includes the upright standard or shaft 1 that is rotatable or oscillatable in the bearings 2, 2, secured firmly on the outside wall of the car adjacent the doorway and forward of the doorway in the direction of travel of the car. The delivery device comprises an upper supporting arm 3 adjustably secured in the socket 4 on the shaft 1, and the lower supporting arm 5 adjustably secured in the socket member 6 on the shaft 1, these arms being parallel, and alined vertically on the shaft to co-act in supporting a mail pouch to be delivered to a station receiving device.

Each arm is provided with a release hook indicated as 7 on the upper arm and 8 on the lower arm, projecting upwardly and downwardly respectively, and except for this difference, they each comprise a pair of spring pressed jaws 9, a bolt 10 passed through the jaws and through the arm, a clamping spring 11 surrounding the bolt, and a retaining nut 12 on the bolt for the spring. Thus the jaws are adapted to receive a ring attached at the end of the mail pouch, and the spring pressing on the jaws retains the ring with sufficient pressure to hold the pouch against dislodgment by wind pressure as the car travels, but when the impact of the pouch striking the receiving forks causes the pouch to double-up, one of the upper jaws is pulled down and one of the lower jaws is pulled up against the tension of their respective springs, and the upper and lower rings of the pouch are thus freed and slide off their respective jaws.

The lower arm is provided with a catcher fork or receiving fork to receive the pouch from the station equipment, the fork being indicated at 13, and the fork at the station may be of the same substantial construction, it being understood that the standard mail

pouches have a restricted middle or waist which adapts them to be received by these forks.

Within the interior of the car an operating lever 14 is provided to co-act with the segmental rack 14' and has a cable 15 passing over a guide pulley 16 and through the car wall to the lever arm 17 at the upper end of the shaft 1, and it will be apparent that a pull on the lever will swing the device around with the pouch hooks at the open door way and the device is held in by the lever and segment, thus permitting attachment of the pouch to be delivered. After the pouch is placed in position the device is swung around to projected position, at right angles to the car wall, as in Fig. 3, by the contractile spring 18 secured to the lever arm on the pin 19 and attached at its other end to the eye bolt 20 projecting from the car wall, the operating lever, however, being manipulated to permit this movement. In addition to the contractile spring 18, a supplemental spring 21 is used, which is attached to the pin 19, but has a chain 22 connecting it to the eye-bolt 20, and inasmuch as the contractile spring 18 is always under tension while the spring 21 is only under tension when the delivery device is swung, by impact, or otherwise, to its extreme position as indicated in Fig. 1, it will be apparent that the first swinging motion of the delivery device as it delivers a pouch, or as it receives the impact of a pouch delivered to it, is against the tension of the spring 18 only, but as the movement progresses the supplemental spring 21 is stretched under tension thus retarding and finally stopping the swinging motion of the device as its arms, loaded with a received pouch, or unloaded, swing into the door way. As the device swings around to position of Fig. 1 the operating lever 14 may drop automatically to latch the device at "in" position, or the lever may be manipulated

lated by hand by throwing it down to position of Fig. 2 where it will hold the delivery device in the position of Fig. 1.

In projected position the delivery device is held stable between the tension spring at one side and the attached cable at the other side, and sufficient rigidity is secured to withstand wind pressure due to the speed of the train, and also due to the natural currents of air. The release hooks on the delivery arms, it will be noted, by the spring pressure on them are well adapted to retain the pouch rings under normal conditions, and yet they permit an easy release of the rings under impact of exchanging mail. 60

What I claim is—

1. The combination with the rotary delivery device having a lever arm and a tension spring urging the device to projected position, means for retracting the device, 65 and an auxiliary spring co-acting with the first spring near the end of the movement of the device to absorb the movement of impact.

2. The combination with the rotary delivery device having an operating lever arm, a retracting lever and a cable connected to said lever arm, a tension spring connected at the other side of the lever arm, and a second, supplemental spring paralleling the 75 first spring, but adapted to co-act therewith only near the end of the movement of the device due to impact.

3. The combination with the rotary delivery device having a lever arm and a tension 80 spring urging the device to projected position, a cable, a retracting lever and a notched segment for retracting and holding in said delivery device, and supplemental means adapted to co-act with the tension spring 85 operable near the end of the movement of the device due to impact.

In testimony whereof I affix my signature.

HERBERT E. SMITH.
